UNITED STATES PATENT OFFICE

ETIENNE OEHMICHEN, OF VALENTIGNEY, FRANCE

DEVICE FOR THE AUTOMATIC ADJUSTMENT OF THE TENSIONS OF FILMS

Application filed August 9, 1927, Serial No. 211,803, and in France August 17, 1926.

The present invention has for its object a device for winding or unwinding any kind of soft strip and particularly a cinematographic film, the arrangement of this device being such that the tension of the film will be automatically adjusted.

According to this invention, this adjustment is obtained in causing alternately the braking or the setting in motion, by means of an independent motive power, of the film carrying spool, through the action of the displacements of a regulating member, on both sides of its position of balance and which is acted upon by the film or strip through the medium of a change of direction effected upon the said regulating member.

The same principle can be applied in various manners without departing from the invention and the appended drawing shows, by way of example, several embodiments which appear as being different although they are based in a direct manner upon the same principle.

Fig. 1 is a perspective view of a first embodiment.

Figs. 2 to 7 refer to modified forms.

From the free portion of the strip which is to be wound or unwound (Fig. 1) is derived a loop 1 included between two stationary rollers 2 and within which is disposed a movable roller 3 under the elastic control of any means (spring, counterweight, or the like) so as to keep the loop in a stretched state; the movements of this stretching roller control a device capable of determining or of stopping the movements of the spool containing the film to be wound or unwound.

In the unwinding operation, the whole is combined in such manner that the setting in motion of the spool 4 takes place when the loop 1 tends to diminish in length and stops when on the contrary the latter tends to extend.

In the winding operations, the drives are reversed, the result remaining the same.

By way of example, the case of winding can be taken into consideration: the movements of the roller forming the loop determine the braking of the planetary pinion

carrying drum 5 of a differential gear, whereof the lateral rings are the one 6 secured to the spool, and the other 7, to an independently driven shaft.

When the loop tends to be reduced in length, in virtue of too great a return of the strip, the roller, through any suitable transmission of motion, loosens the brake 8 acting upon the drum carrying the planetary pinions, at same time this roller acts upon a second brake 9 slowing down the movement of the winding spool. The drum carrying the planetary pinions, when made loose, can no longer transmit its rotary motion to the spool which is on the other hand braked; the said spool then slows down thereby allowing the loop to reassume its normal length.

On the contrary, if the spool does not wind a sufficient quantity of strip, the loop extends, this having for effect to apply the brake of the planetary pinion carrying drum and to immobilize the same gradually, the brake 9 of the spool being at the same time loosened. If in consequence of the lengthening of the loop 1 the brake 8 is applied, the planetary drum is progressively stopped; the movement which is produced by the independent source is therefore progressively imparted to the winding spool so much completely the more the brakeband is applied upon the planetary-drum. When the latter is stopped the speed of the spool is at its maximum. The tendency of the spool to keep this maximum speed continues as long as the braking effect is exerted upon the planetary drum, that is to say that the loop has not got its normal length which corresponds to the normal stress of the film.

If the apparatus is conveniently regulated, very small elongating and shortening movements of the loop will be sufficient to determine the feeding or stopping operation of the spool and it will be possible to obtain a practically constant tension whereof the value can be extremely reduced, the roller exerting its stresses only for operating two brakes which allow powerful effects to be obtained, while requiring but a very small operating stress.

The same mechanism can be used for unwinding purposes in reversing the drives, that is to say in causing the brake to act upon the ring of the differential gear when the loop tends to extend and in loosening the said brake when the said loop tends to become shorter.

A modified form of the device, is indicated in Figure 2 in which the planetary pinion carrying drum 5a receives the motion to be transmitted through a pulley 10a, a toothed wheel or any other means, and in which the brake drums 11 and 12 are secured to the shafts carrying the rings of the differential gear. The motion or the stopping of the spool 4 can be obtained in alternatively acting upon the brakes 13 or 14, by means of the roller device 3 (Fig. 1).

Finally, the differential gear can be replaced by a simple friction clutch combined with a brake. Figure 3 shows an example of this arrangement in which a friction plate 15 operated by a fork 16 and slipping upon the shaft 17 driving the pulley 4e and connected with this shaft through the medium of a long key or of a cone, can be engaged with a drum or a plate 18 which is independently operated or can be braked, in 19, the movements of the fork 15 being in relation with those of the roller 3 (Fig. 1).

In the case of differential gears 5^b, 6^b, 7^b, (Fig. 4) for example, the principle of the invention can be carried out in using two electro-magnets 28^b, 29^b connected with any supply of electric current and controlling each the brake bands 8^b 9^b acting upon the ring carrying the planetary pinions 5^b or upon the shaft carrying the spool 4^b. These two electro-magnets are put in circuit so as to correspond to positions as close together as can be desired of the regulating roller 3^b and thereby allowing an adjustment which is as perfect as possible.

Alterations can be made in the same way in the mechanical driving systems. Thus the device with differential gear can be made of spur wheels in the well known manner; the planetary pinions are then to be grouped in pairs between the wheels 6^c and 7^c, as indicated in Figure 5.

Fig. 6 shows also an embodiment of the invention with a differential gear which is more flat than the previous one. The same comprises a planetary train with epicycloidal gears. As in the case of the differential gear, the system can transmit power or not, according as the planetary pinion carrier 5^d is immobilized or released. Such a device can furthermore be acted upon otherwise, without departing from the principle. For example, the drive can be effected by the external ring, the planetary pinion carrier being released or made idle, or by the planetary pinion carrier itself in releasing or ren-

dering idle either the external ring or the external pinion, and so on.

In this case as in the case of the differential gear, the mechanism comprises a train of gear wheels with planetary motion or not, composed at least of three parts, the first one of which is constituted by the driving shaft and its pinion 7^d, the second one by the shaft of the spool and the corresponding gear 6^d, and the third one by a part 5^d carrying pinions which mesh with the two first ones and is capable of being immobilized or made idle by the play of the brakes operated by the regulating roller.

Finally, in order to simplify the device and to avoid the drives requiring alinement, let us suppose as being collected upon forked member 38, a driving roller 39 operated by a flexible shaft 40 and acting upon a plate 41 connected to the spool 4^d and a braking member 42 (Fig. 7). It is only necessary to cause the whole of this device to swing about an axis 43 to cause the bearing of the roller against the plate to impart motion while the bearing of the brake stops the same. The alternative movement of oscillation and of translation of the part carrying the driving roller 3^d and the brake 42 is controlled by the regulating roller 3^d.

Of course, all these devices are but modified forms of the main device and have been indicated but for the sake of clearness. In fact they are all based upon the principle of the braking of the spool or of the setting in motion of the latter under the influence of the displacements of the regulating roller on both sides of its position of balance.

In all cases, the setting in motion or the stopping must take place within a very short period of time and with very small displacements of the roller. The latter must only require, in order to determine the starting or stopping of the spool, but very small stresses, otherwise detrimental tensions, which it is precisely the purpose to avoid, would be imparted to the strip.

Therefore, it is necessary for the roller to have only to drive parts answering at once with the maximum of action and the minimum of displacement.

The control of a brake band the winding of which can reach and even exceed a full circumference and which can consequently stop a powerful motion with a very small pull of the free run, the closing of an electric contact, the operation of a valve or of a tap, and the like, are precisely fulfilling the required conditions.

The driving power derived from an external supply can thus be wholly transmitted to the spool or suppressed with very small values of the stroke and of the stresses of the regulating roller.

It is obvious that the devices as described can all be gathered upon a same member

carrying all the accessory parts which are necessary to the operation of the whole and that it is possible to secure in one operation the said devices upon the cinematographic apparatus in which it is desired to regulate the tension of the strips either while winding or unwinding is taking place.

Having thus described my apparatus, what I claim as new therein, and my own invention, is:—

1. In a cinematographic apparatus or the like, the combination of a film spool, of a differential gear comprising three members—that is to say two central wheels and a planetary pinion carrier—the one of these members being coupled with the said film spool, driving means for rotating a second of the said members, a brake cooperating with the member coupled with the spool, a second brake cooperating with the third member of the said differential gear and means controlled by the variations of tension of the film and adapted to control both the two said brakes so as to apply the one while the other is released.

2. In a cinematographic apparatus or the like, the combination of a film spool, a differential gear comprising a toothed wheel coupled with this spool, a second toothed wheel and a planetary pinion carrier, means for rotating this said second toothed wheel, a brake adapted to brake the system of the spool and of the wheel coupled therewith, a second brake adapted to brake the planetary pinion carrier, and means controlled by the variations of tension of the film and adapted to simultaneously control the two brakes so as to apply the one and release the other.

3. In a cinematographic apparatus or the like, the combination of a film spool, an epicycloidal differential gear comprising three members—that is to say two central wheels and a planetary pinion carrier—the one of these members being coupled with the said film spool, driving means for rotating a second of the said members, a brake cooperating with the member coupled with the spool, a second brake cooperating with the third member of the said epicycloidal gear and means controlled by the variations of tension of the film and adapted to control both the two said brakes so as to apply the one while the other is released.

4. In a cinematographic apparatus or the like, the combination of a film spool, driving means for rotating this spool, braking means for braking the said spool, and means controlled by the variations of tension of the film and adapted to control both the said driving means and braking means, so as to apply the one while the other is released.

5. In a cinematographic apparatus or the like, the combination of a film spool, driving means for rotating this spool, a brake for braking the rotation of the said spool, and

means controlled by the variations of tension of the film, said driving means comprising clutching means and said means controlled by the variations of tension of the film being adapted to operate both the said clutching means and the said brake so as to unclutch the driving means at the same time the spool is braked and to clutch the driving means at the same time the brake is released.

In testimony whereof I have hereunto af-
fixed my signature.

ETIENNE OEHMICHEN.
